UNITED STATES PATENT OFFICE.

FLORENT PHILIPPE, SR., OF SOUTH CHARLESTON, WEST VIRGINIA.

RAPID TOWEL HANGER.

Application filed May 9, 1921. Serial No. 468,035.

To all whom it may concern:

Be it known that I, FLORENT PHILIPPE, Sr., a citizen of Belgium, and a resident of South Charleston, in the county of Kanawha and State of West Virginia, have invented a new and Improved Rapid Towel Hanger, of which the following is a description.

My invention relates to a towel hanger and has for its general object to provide a device for the indicated purpose of few and simple parts and whereby a towel or the like may be clamped in position with facility and readily removed.

Reference is to be had to the accompanying drawings forming a part of this specification, it being understood that the drawings are merely illustrative of one example of the invention.

Figure 1 is a front elevation of a towel hanger embodying my invention;

Figure 2 is a side view thereof;

Figure 3 is a plan view;

Figure 4 is a fragmentary perspective view on an enlarged scale, parts being omitted;

Figure 5 is a front elevation of the towel hanger on a reduced scale with the towel held by the clamp.

In carrying out my invention in accordance with the illustrated example, a back plate 10 is provided preferably in the form of a plate having holes 11 adapted to receive screws 12 or like fasteners, one of said holes 11 being in a depending extension 13 of the back plate, the lower end 14 of which extension is directed forwardly for a purpose that will appear. The screws 12 serve to secure the hanger vertically on a wall or other support.

On the back 10 are jaws 15 preferably of sheet material and pivotally supported. Retaining means for the jaws 15 consists of a bolt 16 and nut 17. The upper ends of the jaws 15 curve inwardly toward each other and in the opposed edges are concave recesses 18 conforming to a washer 19 on the bolt 16 in the plane of said jaws. The connection is completed by a larger washer 20

outside of the washer 19 and overlapping the adjacent ends of the jaws 15.

A coil spring 21 is disposed transversely between the jaws 15 and secured at its ends to out-turned lugs 22 or equivalent means

on said jaws so that the spring tends to maintain the jaws in the closed position. On the outer edges of the jaws are stops 23 to bear against the side edges of the back plate 10 to limit the inward movement of the jaws and thereby center the same. The washer 20 has formed thereon an extension 24 transversely curved to overlie the spring 21 and constitute a guard therefor. It will be seen from Figure 1 that the opposed inner edges of the jaws 15 above the washer 19 are flaring in an upward direction relatively to each other, so that the jaws are afforded clearance to have a pivotal movement in a common plane about the edge of washer 19, the spring 21 and washer 20 preventing displacement of the jaws.

The adjacent clamping ends of the jaws 15 are formed with flanges 25 directed forwardly and disposed at angles so that the flanges are convergent toward their lower ends to clamp a towel therebetween. Also, the flanges curve laterally outward in opposite directions as at 26. The clamping surfaces 27 of the jaws adjacent to the lower ends of the flanges 25, 26 are formed with protuberances and corresponding depressions or equivalent roughened members to increase the gripping action and below the gripping surfaces the flanges are out-turned on curved lines as at 28.

With the described construction the towel is taken hold of at one corner between the thumb and second finger leaving the corner projecting above the top of the forefinger. The forefinger is employed to force the towel down with a sudden movement between the convergent flanges 25, 26, the pressure serving to spread the jaws against the tension of the spring 21. The downward pressure by the forefinger is continued until the finger passes through the jaws and is arrested by the stop 14, the corner portion of the towel which extends above the forefinger remaining between the jaws to be gripped thereby when the jaws close in response to the reaction of the spring 21, thereby leaving the towel suspended by its corner as indicated in Figure 2.

I would state in conclusion that while the illustrated example constitutes a practical embodiment of my invention, I do not limit myself strictly to the mechanical details herein illustrated, since manifestly the same

can be considerably varied without departure from the spirit of the invention as defined in the appended claims.

Having thus described my invention, I

5 claim:

1. A device of the class described including a back, and spring-pressed jaws mounted on a common pivot at their upper ends on said back, the lower ends of said jaws 10 presenting opposed gripping surfaces approximately in the vertical plane of the pivotal center of the jaws and there being forwardly directed flanges on the jaws at an angle to the plane of the jaws above said 15 gripping surfaces and converging toward the latter.
2. A device of the class described including a back, and spring-pressed jaws pivotally mounted at their upper ends on said 20 back, the lower ends of said jaws presenting opposed gripping surfaces and there being flanges on the jaws above said gripping surfaces and converging toward the latter; together with a stop below the jaws so that 25 a finger pressed downwardly between the jaws to separate the same may have movement toward the said stop to be arrested by the latter.
3. A device of the class described including a back having a depending member di- 30

rected forwardly at its lower edge to constitute a finger stop, and spring-pressed pivotal jaws adapted to clamp the towel or the like and terminating above said stop.

4. A device of the class described including a back, a pivot member projecting forwardly from the face of said back, spring-pressed jaws imposed on said back at the sides of said pivot and presenting concave recesses in their opposed edges at the upper 35 ends of the jaws, there being a round member on said pivot in the planes of the jaws, the sides of said member conforming to said recesses, and clamp means on the pivot bearing against said round member and overlapping the jaws.

5. A device of the class described, including a back, jaws mounted on a common pivot at their upper ends on said back, and flaring downwardly below their point of contact 40 and spring means tending to hold the jaws closed, said jaws adjacent to their lower ends presenting opposed clamping surfaces approximately in the vertical plane of the pivotal center of the jaws and having members above said clamping surfaces convergent toward said surfaces and directed forwardly from the planes of the jaws and then laterally outward in opposite directions.

FLORENT PHILIPPE, Sr.
